(57) **CLAIM**

The ornamental design for a component for a device for examining a body cavity, as shown and described.

DESCRIPTION

FIG. 1 is a first perspective view of a design for a component for a device for examining a body cavity;

FIG. 2 is a second perspective view thereof;

FIG. 3 is a front view thereof;

FIG. 4 is a first side view thereof;

FIG. 5 is a second side view thereof;

FIG. 6 is a top view thereof; and,

FIG. 7 is a bottom view thereof.
